UNITED STATES PATENT OFFICE.

PAUL KUHNE, OF BIRMINGHAM, ALABAMA.

BAR SUPPORTER AND DIVIDER FOR CONCRETE SLABS.

1,833,120.

Specification of Letters Patent.

Patented Mar. 9, 1920.

Application filed July 28, 1919. Serial No. 313,911.

To all whom it may concern:

Be it known that I, PAUL KUHNE, a citizen of the United States, residing at 2300 Orange avenue, Birmingham, State of Alabama, have invented certain new and useful Improvements in Bar Supporters and Dividers for Concrete Slabs, of which the following is a specification.

This invention relates to improvements 10 in bar supporters and dividers for concrete slabs.

The object of the invention is to provide simple and inexpensive means for conveniently supporting and securing reinforcing 15 bars at any required distance in concrete slab construction, so that the reinforcing bars cannot shift while the concrete is being put in.

A further object of the invention is to 20 provide a support adapted to engage reinforcing bars at definite distances in the length of a slab, and to hold said bars in fixed relative position from the ceiling when putting in the concrete.

25 The invention also comprehends improvements in the details of construction and arrangement of parts which will be herein-after described and particularly pointed out in the claims.

30 In the drawings:—

Figure 1 is a perspective view of my improved support illustrating a bar in position.

Fig. 2 is a plan view of the same.

35 1 indicates a flat strip of metal, provided on its opposite longitudinal edges with right angular cuts 2, to form edge tongues 3. The metal forming the tongues is bent downwardly to form means for anchoring the support in the concrete, while the cut-outs 40 act as seats in which the concrete engages. Both longitudinal edges of the support have these cut-outs and tongues, which insures steadiness of position when in use. The cut-outs on one side are disposed out of alignment with the cut-outs on the opposite side, hence the tongues on one side are disposed in a plane intermediate the tongues on the opposite side.

Intermediate the cut-outs on the longitudinal edges and disposed throughout the length of the support are two rows of prongs or tongues 6, formed by cutting out the metal and bending same upwardly at an incline. These prongs extend in an opposite direction from the tongues 3, hence affording a positive anchor when the support is em-

bedded in the mass of concrete. There are preferably two parallel rows of prongs, the prongs of one row being disposed to overlap the plane of the ends of the adjacent 60 row. In addition to the prongs acting as anchoring means, they also serve as a means for fastening binding rods 7, in position. These rods are usually placed a definite distance apart, and the rows of prongs are arranged so that by employing the prongs of one row the bars will be a certain distance apart; while if this distance is to be decreased, and a greater number of bars is to be provided, then the companion row of 70 prongs will be brought into use. The invention therefore not only provides special means for anchoring the support in concrete, but in addition it affords specific and safe means for effectively holding the reinforcing 75 bars locked in set position. Consequently when the mass of concrete is placed around the support, and the bars, the whole structure is reinforced throughout. The prongs are bent around the bars to embrace same as 80 tightly as possible, and when the concrete is put in place it flows, or is packed around the bent portion and forms an effective binder. The concrete also passes through the openings formed by the tongues, consequently 85 stresses in all directions are taken care of.

While the invention described acts as a means for reinforcing the concrete, its prime importance is to form means for rigidly holding the reinforcing bars in the ceiling 90 when putting in the concrete.

What I claim is:—

1. A support for concrete comprising a flat strip of metal having two longitudinal edges provided with cut-out portions and 95 depending tongues adjacent said cut-out portions, said tongues being formed by the metal from the cut-out portions, the cut-out portions on one edge being out of alignment with the cut-out portions on the opposite edge, the flat strip having two longitudinal rows of prongs all extending in the same direction and from end to end of the strip and extending upwardly from the surface of the strip, the prongs of one row being disposed 100 to overlap the plane of the ends of the adjacent row, and bars extending across the strip and secured by bending certain of the prongs over said bars.

2. A support of the character described 110 comprising a flat metal plate, projections on opposite longitudinal edges, with a plural-

ity of projections, the projections on one edge being out of alinement with the projections on the opposite edge, the metal at one end of each projection being bent to 5 form tongues, rows of prongs cut out of and extended from the metal plate between the cut out edges, the rows of prongs extending

throughout the length of the plate, the free ends of the prongs in one row terminating beyond the fixed end of the prongs of the 10 adjacent row.

In testimony whereof I affix my signature.

PAUL KUHNE.
